UNITED STATES PATENT OFFICE.

JOHN HOFFMANN, OF SHEBOYGAN, WISCONSIN.

BRICK-CLEANING MACHINE.

Application filed April 25, 1922. Serial No. 556,483.

To all whom it may concern:

Be it known that JOHN HOFFMANN, a citizen of the United States of America, residing at Sheboygan, in the county of 5 Sheboygan and State of Wisconsin, has invented new and useful Improvements in Brick-Cleaning Machines, of which the following is a specification.

The object of the invention is to provide 10 a simple and efficient machine whereby bricks which have been used may be cleaned or relieved of adhering mortar or other substances to permit of again using the brick and of laying the same with accuracy in a 15 new wall or structure; and in this connection to provide a cleaning device which will operate effectively and expeditiously with the minimum of manual intervention or control; and with these objects in view the 20 invention consists in a construction and combination of parts of which a preferred embodiment is shown in the accompanying drawings, wherein:—

Figure 1 is a plan view of a machine embodying the invention.

Figure 2 is a side view of the same viewed from the outlet or discharge side thereof.

Figure 3 is a side view from the opposite side.

Figure 4 is a sectional view on the plane indicated by the line 4—4 of Figure 1.

The machine embodies essentially a conveyor 10 upon which the bricks to be cleaned are adapted to be deposited successively or 35 in series and each on its side edge so as to expose the side surfaces thereof in opposite directions laterally; and this conveyor is designed to deposit the bricks upon a transfer table 11 which is adapted to be tilted to 40 deposit the same upon a supplemental conveyor 12 moving in a plane at right angles to that of the main and initial conveyor, said second or supplemental conveyor being adapted to receive the bricks in a flat position 45 so as to expose the end edges thereof laterally in opposite directions.

Disposed midway or intermediately of the path of the machine or primary conveyor at opposite sides of the vertical plane thereof are 50 cleaning members 13 adapted for contact with the opposite side or flat surfaces of the bricks as they successively pass between said cleaning members to the end that any adhering material such as mortar may be removed therefrom, and arranged midway or intermediately of the length of the supplemental

or secondary conveyor, which in the construction illustrated consists of a plurality of parallel belts as shown, there is arranged a plurality of cleaning members 14 adapted 60 for contact with the end edges of the bricks as they successively pass therebetween, to remove any material adhering thereto.

In the construction illustrated the main or primary belt is carried by rollers or 65 drums 15 and 16 of which the former carried by a shaft 17 receives its motion from an attached gear 18 which may be driven by any suitable power or from any preferred source, not shown. The spindle 19 of the drum 16 70 is connected by intermeshing bevel gears 20 with the spindle or shaft 21 of pulleys 22 which carry the belts of the auxiliary or secondary conveyor 12, and said shaft 21 also preferably carries an eccentric 75 which is arranged in operative relation with a tilting lever 24 yieldingly held in its normal position by a spring 25 and provided with a push rod 26 for causing the tilting movement of a plate which constitutes the transfer device 11 and which is pivotally mounted as at 27 upon the platform 28 of the machine in spanning relation with the auxiliary or secondary conveyor 12.

In the construction illustrated each of the 80 cleaning members designed for operation with relation to the surfaces of the bricks to remove adhering mortar or other material consists of a spindle 29 carrying a plurality of blades or knives 30, and rotary motion in 85 opposite directions is communicated to the spindles of the side cleaners 13 by means of intermeshing gears 31 which receive their motion from a countershaft 32 in turn actuated by the drive gear 18 through a train of 90 gears 33. The countershaft 32 communicates motion to the second countershaft 34 through the gears 35, and motion is communicated from the countershaft 34 to the spindles 36 of the end cleaners 14 by the 95 intermeshing gears 37.

Thus in operation it is only necessary for 100 the operator to place the bricks in the proper relations and positions on the main or primary conveyor 10 whereupon they are carried forward between the cooperating main or side cleaning members and deposited upon the transfer table from which they are conveyed by the tilting movement thereof through the action of the eccentric 23 to the 105 supplemental or secondary conveyor and thereby conveyed between the end clean-

ing members 14 for the removal of adhering material from the end edges thereof, after which the same may be deposited in the suitable receptacle, not shown, or removed for 5 subsequent use in building operations.

Having described the invention, what is claimed as new and useful is:—

1. A brick cleaning apparatus having main and secondary conveyors disposed for 10 operation in paths arranged in perpendicular relation, cleaning members arranged at opposite sides of each of said conveyors for acting upon the exposed outer surfaces of bricks carried therebetween, and a transfer 15 mechanism for receiving bricks from the main or primary conveyor and depositing them upon the supplemental or secondary conveyor.

2. A brick cleaning apparatus having 20 main and secondary conveyors disposed for operation in paths arranged in perpendicular relation, cleaning members arranged at opposite sides of each of said conveyors for acting upon the exposed outer surfaces of bricks 25 carried therebetween, and a transfer mechanism for receiving bricks from the main or primary conveyor and depositing them upon the supplemental or secondary conveyor, the cleaning members consisting of rotary devices having outwardly projecting blades for cutting engagement with material adhering to the surfaces of the bricks.

3. A brick cleaning apparatus having main and secondary conveyors disposed for 35 operation in paths arranged in perpendicular relation, cleaning members arranged at opposite sides of each of said conveyors for acting upon the exposed outer surfaces of bricks carried therebetween, and a transfer 40 mechanism for receiving bricks from the

main or primary conveyor and depositing them upon the supplemental or secondary conveyor, the transfer mechanism having a tilting table and means for periodically actuating the same. 45

4. A brick cleaning apparatus having main and secondary conveyors disposed for 50 operation in paths arranged in perpendicular relation, cleaning members arranged at opposite sides of each of said conveyors for 55 acting upon the exposed outer surfaces of bricks carried therebetween, and a transfer mechanism for receiving bricks from the main or primary conveyor and depositing them upon the supplemental or secondary conveyor, the transfer mechanism having a tilting table axially disposed in transverse relation with the supplemental or secondary conveyor and means for periodically actuating the same. 60

5. A brick cleaning apparatus having main and secondary conveyors disposed for 65 operation in paths arranged in perpendicular relation, cleaning members arranged at opposite sides of each of said conveyors for 70 acting upon the exposed outer surfaces of bricks carried therebetween, and a transfer mechanism for receiving bricks from the main or primary conveyor and depositing them upon the supplemental or secondary conveyor, the transfer mechanism consisting of a tilting table, an eccentric and means for operating the same in timed relation with the conveyors, a locking lever for 75 actuation by the eccentric, and a push rod connection between said lever and the tilting table.

In testimony wherof he affixes his signature.

JOHN HOFFMANN.
